UNITED STATES PATENT OFFICE.

HENRY GAGE HOOK, OF CHICAGO, ILLINOIS.

ACCOUNT-BOOK.

1,083,280.

Specification of Letters Patent.

Patented Jan. 6, 1914.

Application filed May 18, 1908. Serial No. 433,507.

To all whom it may concern:

Be it known that I, HENRY GAGE HOOK, a citizen of the United States, residing at Chicago, in the county of Cook and State 5 of Illinois, have invented certain new and useful Improvements in Account-Books, of which the following is a specification.

This invention relates in general to blank books in which accounts or entries of any 10 kind are designed to be kept in alphabetical order, although more especially intended for such books as ledgers, dockets, registers, and the like where a large number of entries or 15 accounts are kept, and it is especially applicable to a loose leaf book that is capable of being expanded.

The principal object of the invention is to so arrange and distribute the alphabetical index sheets employed that any particular name, entry, account or the like, and its 20 location in the book, may be readily determined.

Another object of the invention is to provide a book of the character described 25 adapted to carry the greatest number of accounts on the least number of sheets, whereby considerable time may be saved to the user of the invention in ascertaining the location of any desired entry, and less material is employed in a single book, as compared with other books having a similar 30 purpose and adapted to carry the same number of accounts or entries.

To these and other minor ends which will 35 hereinafter appear, my invention consists in a book for accounts and other entries having the peculiarities of structure and arrangement, especially as relates to the distribution of the index sheets, as hereinafter 40 described and more particularly pointed out in the claims.

My invention will be readily understood when considered in connection with the accompanying drawings illustrating practical 45 embodiments thereof, in which—

Figure 1 is a broken perspective view of my improved account book, the same being shown as opened to expose the first index sheet therein. Fig. 2 is a fragmentary plan 50 view of another index sheet of the same character as that appearing in Fig. 1, this view also showing certain of the tabs and identifying numerals of underlying sheets of the book. Fig. 3 is a fragmentary view 55 with certain of the sheets turned back and exposing a series of interposed supplemen-

tal entry sheets designed to carry special and frequently used accounts.

Referring now to the drawings, 4 designates as an entirety an account book, such as a ledger, between the covers of which are bound, preferably under the loose-leaf system, a number of entry sheets 5 of any usual or approved form, between which entry sheets are distributed at intervals a number of index sheets 6. Each index sheet 6 is ruled vertically and horizontally, as shown, providing a plurality of rectangular spaces or squares 7, in the inner vertical row of which squares are printed a series 8 of consecutive numerals, such as 1 to 10, the upper horizontal row of such squares also bearing a row 9 of consecutive numerals corresponding with said vertical row. In the oblique row of spaces which align with both the horizontal and vertical rows thus identified by numerals are printed letters indicating alphabetical divisions, these latter being indicated at 10.

A great many alphabetical divisions for 80 index purposes are known, such divisions varying widely in extent according to the size of the book in which they are employed and the number of entries to be served thereby, and, of course, any convenient or suitable group or system may be employed in 85 connection with my invention.

Each index sheet is cut away along its upper margin, as shown at 11, to expose 90 therebeneath the upper right-hand corner portions of the series of entry sheets 5 lying between said index sheet 6 and the next succeeding index sheet, these underlying entry sheets being each similarly cut away to graduated extents, as shown at 12, and the 95 exposed corners of each of said sheets bearing a row 13 of consecutive numerals above and corresponding with the immediate underlying row 9 of said numerals on the index sheet.

To the outer margin of each index sheet is attached an index tab 14, each tab bearing an alphabetical index corresponding to the last or lowermost of the alphabetical indices printed on the index sheet, although, 105 where a single index sheet covers all the divisions of a single letter, the tab may have printed thereon simply that letter: and these index sheets are distributed at intervals throughout the book, with the entry sheets 110 between any two consecutive index sheets. The tabs 14 are, of course, grouped and ar-

ranged across the free edge of the book so that each will be plainly visible and accessible, as usual in books of this character, Fig. 1 showing two rows of such tabs, the lower row projecting beyond the outer edge of the upper row.

To ascertain the location of any particular entry, the book is opened to expose the index sheet under which such entry falls, 10 and this sheet showing in one of its vertical columns the specific location of such entry, the latter is found by simply placing the thumb on the exposed numeral of the entry sheet at the head of said column, and then 15 turning back all of the preceding index and entry sheets. For instance, assuming that it is desired to find an entry under the name of "Alton". The thumb of the user is placed on the marginal tab "A" and the book is opened to expose the index sheet to 20 which this tab is attached, as shown in Fig. 1. The name "Alton" is found under column 8. The user then places his thumb upon the exposed numeral 8 of the series of 25 underlying entry sheets, and throws back all of the preceding sheets, and the "Alton" account will thus be found on entry sheet "8" under index sheet "A".

Under ordinary conditions the main 30 entry sheets alone such as any of the series 5, are sufficient; but it not infrequently happens that, among the accounts kept in such a book, there are a few large or frequently used accounts, requiring considerably more 35 space in the book than the average account, and hence it is desirable to provide, in association with the main account or entry sheet for any one or more alphabetical division as indicated on the index sheet, one or more 40 additional or supplementary entry or account sheets, with means for readily identifying the latter. These supplemental sheets, when employed, are inserted directly in front of the main entry sheet pertaining to 45 that alphabetical division under which such special account or accounts fall; and Fig. 3 of the drawings illustrates the typical use of such supplemental sheets. Let it be assumed that there are, under the index 50 "CHA" a number of accounts, such as "Chase", "Chapman", "Chandler", etc. Supplemental entry sheets 55, cut away so that the upper right-hand corner of each will be exposed when all of the preceding index and entry sheets have been turned back, are inserted in front of the main entry sheet 60 "9", and, preferably, the name or names identifying the entries or accounts carried on these supplemental sheets are written or 65 printed on the exposed corner portions of said sheets, as clearly indicated in Fig. 3; and it will be observed that the undermost of this series of supplemental sheets is cut away sufficiently far back so as to be undisturbed when the preceding entry sheet

"8" is thrown back. To illustrate the use of the book in connection with these supplemental entry sheets, let it be assumed that a frequently used account under the name of "Chapman" is to be found. The book 70 is first opened to expose the index sheet identified by the tab "CI", shown in Fig. 2. As the name "Chapman" falls under the specific index "CHA", the book is further opened by placing the thumb on the upper 75 index figure 9 and throwing back the index sheet and all of the main entry sheets preceding entry sheet "9", as is indicated in Fig. 3. This exposes the name "Chapman" on the upper corner of the next to the lowest 80 of the supplemental sheets; and by placing the thumb on the name "Chapman" and again throwing back all of the overlying or preceding supplemental entry sheets (if any such there be), the "Chapman" account is 85 brought to view. These supplemental entry sheets may be inserted in any desired numbers and at any desired places according to the requirements of each individual user of the book, for which purpose a loose-leaf system is especially well adapted.

While, in order to accommodate large accounts or an unusual number of small accounts occurring under any particular specific alphabetical division, any or all of the 95 entry sheets identified by the numbers at the upper right-hand corners thereof may be duplicated or multiplied to any desired extent, yet, the use of the specific supplemental sheets as above indicated is preferable, as saving considerable time in hunting through a number of similarly identified individual entry sheets. Where a single supplemental entry sheet is in itself insufficient to carry the account or accounts under the 100 special heading of said sheet, it may, of course, be duplicated or multiplied by underlying sheets cut away to the same extent as the first sheet. It will thus be seen that the general scheme and arrangement of the 110 supplemental entry sheets, where employed, is the same as that of the main entry sheets.

It is evident that the particular mode of ruling and marking the index sheets as herein shown and described might be considerably varied without departing from the principle or sacrificing any of the advantages secured thereby; and hence I do not limit the invention to the particular form of index sheet illustrated and described, except to the extent clearly indicated in specific claims.

I claim:

1. A book for accounts and other entries, comprising a series of index sheets each 125 bearing alphabetical indices arranged in alphabetical succession across the face thereof, and a plurality of groups of entry sheets interposed between adjacent index sheets, the entry sheets of each group being cut 130

- away in graduated amounts along their upper margins, and the exposed portions of said entry sheets bearing identifying characters arranged respectively in vertical alinement with the several indices on said index sheet, substantially as described. 70
2. A book for accounts and other entries, comprising a series of index sheets each ruled to present vertical columns having a row of successive numerals in and across said columns, and also a row of successive alphabetical indices arranged in alphabetical order across said columns, and a plurality of groups of entry sheets interposed between adjacent index sheets, the entry sheets of each group being cut away in graduated amounts along their upper margins, and the exposed portions of said entry sheets bearing a row of numerals similar to that on the controlling index sheet, said numerals being in vertical alinement respectively with like numerals and with the alphabetical indices on said index sheet, substantially as described. 75
- 10 20 25 30 35 40 45 50 55 60 65 70 75 80 85 90 95 100 105 110 115 120 125 130
3. A book including a group of leaves arranged in a set and cut away along one edge so as to leave exposed portions which are arranged in a stepped series, and having on said exposed portions page-indicating characters and a separate index for the said set of ledger leaves, appearing upon the uppermost leaf of the set and alphabetically sub-divided, the said divisions being arranged respectively opposite the exposed portions of the leaves. 95
4. A book including a group of leaves arranged in sets which are cut away along one edge so as to leave exposed portions arranged in a stepped series and having on said exposed portions page-indicating characters and a separate index for each set of leaves, appearing upon the uppermost leaf of the set and alphabetically sub-divided, the said divisions being arranged respectively opposite the exposed portions of the leaves. 100
5. A book having leaves arranged in sets which are cut away along one edge so as to leave exposed portions arranged in stepped series, the numbers of the pages of the book appearing upon the said exposed portions, and an index for the book divided into sections corresponding with the aforesaid sets of leaves, each section appearing upon a separate sheet that is arranged as the uppermost leaf of each set, and the index being alphabetically sub-divided, and the sub-divisions being respectively designated by the numbers of the pages of the book covered by said sub-divisions. 105
6. A book including a group of leaves arranged in a set and cut away along one edge so as to leave exposed portions which are arranged in a stepped series, and having on said exposed portions page-indicating characters and a separate index for the said set of ledger leaves, appearing upon the uppermost leaf of the set and characteristically sub-divided, the said divisions being arranged respectively opposite the exposed portions of the leaves. 110
7. A book for accounts and other entries, comprising a series of index sheets each bearing alphabetical indices arranged in alphabetical succession across the face thereof, and a plurality of groups of entry sheets interposed between adjacent index sheets, the entry sheets of each group being cut away in graduated amounts along one of their margins, and the exposed portions of said entry sheets bearing identifying characters arranged respectively in vertical alinement with the several indices on said index sheet, substantially as described. 115
8. A book for accounts and other entries, comprising a series of index sheets each ruled to present vertical columns having a row of successive numerals in and across said columns, and also a row of successive alphabetical indices arranged in alphabetical order across said columns, and a plurality of groups of entry sheets interposed between adjacent index sheets, the entry sheets of each group being cut away in graduated amounts along one of their margins, and the exposed portions of said entry sheets bearing a row of numerals similar to that on the controlling index sheet, said numerals being in vertical alinement respectively with like numerals and with the alphabetical indices on said index sheet, substantially as described. 120
9. A book, comprising a group of sheets cut away along one edge so as to expose portions of the faces of the sheets in a stepped series, a subdivided index with characters of identification, the sub-divisions of the index having definite relation, in arrangement, respectively to the successive exposed stepped sheets, and supplemental sheets arranged between sheets primarily identified by the characters of the index, the inserted supplemental sheets being cut back along their edges to greater extent than are the sheets between which they are placed. 125
10. A book, comprising a group of sheets cut away along one edge so as to expose portions of the faces of the sheets in a stepped series, a sub-divided index with characters of identification, the sub-divisions of the index having definite relation, in arrangement, respectively to the successive exposed stepped sheets, and supplemental sheets arranged between sheets primarily identified by the characters of the index, the inserted supplemental sheets being cut back along their edges in stepped series each to a greater extent than are the sheets between which they are placed, and the supplemental sheets being designated by characters on their exposed portions. 130

11. A book for accounts and other entries, comprising a series of index sheets each bearing numerals and successive alphabetical indices arranged in vertical columns 5 having a row of successive numerals in and across said columns, the successive alphabetical indices being arranged in alphabetical order in and across said columns, and a plurality of groups of entry sheets interposed between adjacent index sheets, the entry sheets of each group being cut away 10 in graduated amounts along their upper

margins, and the exposed portions of said entry sheets bearing a row of numerals similar to that on the controlling index sheet, 15 said numerals being in vertical alinement respectively with like numerals and with the alphabetical indices on said index sheet, substantially as described.
